UNITED STATES PATENT OFFICE.

ELIAS M. SPARKS, OF ALGONA, IOWA.

POST.

Application filed June 14, 1927. Serial No. 198,801.

This invention relates to improvements in the construction of posts as for example fence and sign posts and has as its general object to provide a post which will present 5 advantages over both wooden and metal posts.

It is a well known fact that wooden posts, when rotted, must be completely replaced, and while such posts are not objectionable 10 for use in fencing in fields, they present an unsightly appearance if employed in the vicinity of a home, as the posts are of necessity of more or less irregular contour, and likewise they soon become discolored when 15 exposed to the elements. Therefore the present invention has as one of its objects to provide a post which will be more durable than a wooden post and which will present a neater and more attractive appearance.

Another object of the invention is to provide 20 a post of composite structure and consisting of a core of wood and a sheath of metal, and which post will therefore possess all of the desirable qualities and the advantages 25 of both a wood post and a metal post, the construction being such that fence wires, signs, mail boxes, and the like, may be secured to the post with the same facility as to an ordinary wooden post and by the use 30 of ordinary fastening means such as nails, screws, or bolts, and will be more securely anchored than when secured directly 35 to a wooden post. In this respect the invention distinguishes over a metal post in that, in connection with such a post, in mounting 40 wires, signs, or mail boxes thereon, it is necessary to employ specially designed attaching or fastening means or to drill holes through the post to accommodate securing bolts.

Another object of the invention is to so construct the post embodying the invention that the wood core thereof will be effectually protected from the elements by the sheath 45 of the post and yet with the provision of means whereby securing elements may be readily driven into the core for the purpose of securing fence wires, signs, mail boxes, or any other objects, to the post by the use of 50 the common types of securing devices.

Another object of the invention is to provide 55 a post of composite construction and embodying a core and a sheath, the construction and arrangement of the component parts of the post being such that fence wires anchored to the post will be securely held

against longitudinal displacement so that if the wires are properly stretched at the time they are strung, there can be no sagging 60 of the wires nor any loosening of wires between adjacent posts in the event of breakage of any one of the wires.

Another object of the invention is to so construct the post that the core thereof may be readily replaced when occasion requires, 65 although the construction is such that the core will be effectually protected from the elements and therefore be exceptionally durable.

In order to preserve wood posts it is customary 70 to impregnate the same with creosote or some other agent to prevent deterioration or rotting of the posts, but where the posts are continuously and completely exposed to the elements, the impregnating medium soon loses 75 its strength and efficiency and furthermore the treated surface of the post is exposed to contact by the clothing of one approaching the post. Therefore the present invention has as a further object to so 80 construct the post that the wood core thereof may be impregnated with a preservative fluid such as creosote and substantially the entire surface of the core shielded from the elements so that the preservative will retain 85 its strength for an indefinite period of time thus greatly prolonging the life of the post as a whole.

While the accompanying drawings and the description which is to follow, constitute a 90 disclosure of the preferred embodiment of the invention, it will be understood that various changes may be made within the scope of what is claimed.

In the accompanying drawings:

Fig. 1 is a front elevation of a post constructed in accordance with the present invention, the post illustrated in the said figure being employed in supporting fence wires;

Fig. 2 is a vertical front to rear sectional view through the post shown in Figure 1;

Fig. 3 is a horizontal sectional view taken substantially on the line 3—3 of Figure 1 looking in the direction indicated by the 105 arrows;

Fig. 4 is a horizontal sectional view on the line 4—4 of Figure 1 looking in the direction indicated by the arrows;

Fig. 5 is a view similar to Figure 3 but 110 taken on a plane slightly lower than the plane of Figure 3 and on a larger scale.

While the post embodying the invention is designed for universal use, it is illustrated in the drawings as employed primarily for the support of fence wires, the wires being indicated in the drawings by the reference letter W.

The post comprises a core which is indicated in general by the reference numeral 1 and a sheath which is indicated in general by the reference numeral 2. The core 1 is of wood of any kind found suitable for the purpose and, in view of the fact that the core is to be protected by the sheath, in a manner which will presently be made clear, the core 15 may be made from wood of cheaper grade than that employed in the manufacture of all-wood fence posts, thus effecting an economy in the manufacture of the posts of the invention. The wood core 1 is rectangular 20 in cross section and of a length corresponding to the height of the fence to be erected, taking into consideration, of course, the portion of the length of the said post which is to be embedded in the ground. Before assembling the core with the sheath, to be presently described, the core is immersed in or otherwise treated with creosote or some other preservative liquid until impregnated thereby. While the core 1 is illustrated in the drawings 25 as square at its lower end, as well as at its upper end, it will be understood that the lower end of the core might be of tapered or pointed formation to facilitate the anchorage of the post in the ground, if desired, and 30 without departing from the spirit of the invention.

The sheath of the post may be made of cast metal or sheet metal and the said sheath is of hollow rectangular form and comprises 40 side walls 3, a rear wall 4, and front wall portions 5, the walls 3 occupying planes at right angles to the rear wall 4, and the front wall portions 5 occupying a plane at right angles to the side walls 3. Interiorly the 45 sheath is of a width equal to the width or thickness of the core 1 but preferably of slightly greater dimensions from front to rear than the corresponding dimension of the core, so that while the core is snugly engaged by 50 the inner surfaces of the side walls 3 and rear wall 4, the wall portions 5 at the front of the sheath are slightly spaced with respect to the corresponding face of the core. These 55 wall portions 5 have their margins turned inwardly as indicated by the numeral 6 so that the edges of the wall portions snugly engage against the front side of the core 1 as clearly shown in Figures 3, 4 and 5 of the drawings. The inturned edges 6 of the front wall portions 5 are somewhat spaced, in practice about one-half an inch, so that a narrow vertical portion of the front face of the core 1 is exposed between these edge portions. In 60 overturning the margins of the front wall portions 5 to form the inturned edges 6, the

metal is bent to rounded or curved form as best shown in Figures 3, 4 and 5 of the drawings. It will now be evident that staples, nails or screws may be driven into the core 1 through the front of the sheath at the portion thereof bounded by the inturned edges 6 of the front wall portions 5 of the sheath.

As illustrated in Figures 1, 2, 3 and 5 of the drawings, the fence wires W are strung across the face of the post, and staples 7 are disposed in vertical position to straddle the wires and are driven into the core 1. In driving the staples into place, the portions of the fence wires engaged by the shanks of the staples, will be deflected or bent inwardly so as to extend over the rounded outer surfaces of the inturned edges 6 of the front wall portions 5, the shanks of the staples being accommodated between the inturned edges as best shown in Figures 3 and 5 of the drawings. Due to the bends formed in the fence wires at the points of engagement of the staples therewith, the fence wires are very securely anchored to the post and longitudinal displacement of the wires is positively prevented. At the same time, due to the rounded cross sectional contour of the ordinary staples and the rounded surfaces of the inturned edges 6 of the front wall portions 5 of the sheath of the post, the bends formed in the wires will not be so acute as to weaken the wires, nor will the wires be engaged by any sharp edges which would be liable to cut into the wires and cause weakening thereof. Inasmuch as the exposed portion of the core extends for the entire height of the post, as a whole, it is quite evident that the fence wires may be strung at any desired elevation and that any number of fence wires may be secured to the post. It is likewise evident that woven wire fencing may be secured to the post embodying the invention by means of staples disposed to straddle the meshes of the wiring.

In order that the sheath 2 may be reinforced so as to prevent any spreading of its sides 3, although this will be unlikely to occur, in any event, due to the fact that the post is anchored at its lower end in the ground and is provided with an encompassing cap member at its upper end, as will be presently explained, reinforcing members indicated in general by the numeral 8 are employed and each of these members is preferably formed from a length of bar metal bent 110 to provide spaced side portions 9 and an intermediate portion 10, the reinforcing members 8 being so proportioned as to adapt them to be fitted snugly to the sheath of the post from the front thereof, with the side 115 members 9 engaging against the outer sides of the side walls 3 of the sheath and the intermediate portion 10 engaging against and extending transversely of the front portions 120 of the said sheath. The intermediate por- 125

tion 10 of each of the reinforcing members is formed intermediate its ends with an opening 11, and a nail or other securing element 12 is driven through the opening and into the core 1 of the post, the reinforcing member being in this manner securely anchored to the post and in position to brace the sides thereof.

The cap member referred to above is indicated by the numeral 13 and comprises a top portion 14 and a depending marginal flange 15 which extends about the four sides of the top portion and encompasses the upper end of the sheath 2, the flange 15 serving of course to snugly embrace the walls of the sheath at the upper end of the sheath and thus reinforce the said walls, and the top member 14 of the cap serving to prevent the entrance of moisture into the sheath through the upper end thereof and to protect the upper end of the core 1 from the elements. In order that the cap member may be firmly secured in place, the top portion 14 thereof is formed centrally with an opening 16, and a nail or other suitable fastening element 17 is driven through this opening and into the upper end of the core.

As previously stated the post embodying the invention is not limited to use as a fence post but may likewise be employed in supporting signs or mail boxes or any other articles or objects.

Inasmuch as the core 1 is not in any way secured within the sheath, it is evident that in the event of rotting of the core, it may be extracted from the sheath and a new core driven into place in the sheath. Therefore the invention contemplates a post which will be exceptionally durable, which is neat and attractive in appearance, and which possesses all of the advantages of wood and metal posts, and none of the disadvantages thereof.

Having thus described the invention, what I claim is:

1. A post comprising a core of wood, and a metal sheath enclosing the core and including walls embracing the faces of the core, one of said walls comprising spaced wall portions having their relatively adjacent edges relatively spaced whereby to expose a portion of the surface of the core, the said edge portions being transversely rounded.

2. A post comprising a core of wood, and a metal sheath enclosing the core and including walls embracing the faces of the

core, one of said walls comprising spaced wall portions having their relatively adjacent edges relatively spaced whereby to expose a portion of the surface of the core, the said edge portions being transversely rounded and having their margins contacting the adjacent face of the core.

3. A post comprising a core of wood, a metal sheath enclosing the same and having one wall divided longitudinally to expose a portion of the surface of the core, whereby fastening elements may be driven into the core through the division of the said wall, and a reinforcement for the sheath having portions to embrace the side walls of the sheath and an intermediate portion to extend across the said divided wall.

4. A post comprising a core of wood, a metal sheath enclosing the same and having one wall divided longitudinally to expose a portion of the surface of the core, whereby fastening elements may be driven into the core through the division of the said wall, and a reinforcement for the sheath having portions to embrace the side walls of the sheath and an intermediate portion to extend across the said divided wall, and a securing element driven through the last mentioned portion of the reinforcing member and into the said core.

5. A post comprising a core of wood, a metal sheath enclosing the core and including walls embracing the faces of the core, one of said walls comprising spaced wall portions having their relatively adjacent edges relatively spaced whereby to expose a portion of the surface of the core, said end portions being curved inwardly throughout their length with their inner margins contacting the adjacent face of the core, the engagement of the said inturned margins with the said face of the core serving to space the said spaced wall portions from the said face of the core and define a channel of appreciable depth bounded by the said edge portions into which channel a portion of a fence wire straddled by a securing staple driven into the core through the channel may be distorted to provide a locking bend in the wire positioned between said edge portions of the spaced wall portions.

In testimony whereof I affix my signature.

ELIAS M. SPARKS.
